United States Patent Office

Des. 232,737

Patented Sept. 10, 1974

232,737

TELEVISION ANTENNA

Dominick Padilla, New York, and Arthur A. Fink,
Yonkers, N.Y., assignors to RMS Electronics, Inc.,
Bronx, N.Y.

Filed Mar. 15, 1972, Ser. No. 335,114

Term of patent 14 years

Int. Cl. D14—03

U.S. Cl. D26—14 F

FIG. 1 is a perspective view of an antenna embodying our novel design;

FIG. 2 is a top plan view thereof;

FIG. 3 is a rear elevational view thereof;

FIG. 4 is a front elevational view thereof;

FIG. 5 is a side elevational view thereof, looking from the right of FIG. 1; and

FIG. 6 is a bottom plan view thereof.

We claim:

The ornamental design for a television antenna, substantially as shown.
